WRENCH

Filed Aug. 25, 1927

UNITED STATES PATENT OFFICE.

WILLIAM HENRY GOLDSTRAW, OF COBDEN, VICTORIA, AUSTRALIA.

WRENCH.

Application filed August 25, 1927, Serial No. 215,450, and in Australia August 26, 1926.

This invention relates to an adjustable wrench of improved construction which in use will be found to be highly efficient in maintaining a tight grip on a nut or other work piece required to be rotated.

The improved wrench consists essentially of a fixed jaw, a movable jaw slidable on said fixed jaw and a lever handle pivoted to the fixed jaw and so connected to the movable jaw that when the wrench is actuated by its lever handle the movable jaw is caused to automatically tighten on the nut or work piece.

In the accompanying exemplary drawings:—

Figure 1 is a view in elevation of the improved wrench.

Figure 2 is a longitudinal section on the line 2—2 of Figure 3.

Figure 3 is a cross-sectional view on line A—A of Figure 1.

The wrench comprises a fixed jaw 2 constructed with a downwardly extending shank 3 which slidably supports a movable jaw member 4. The shank 3 is slotted to form two arms 5 which are accommodated in recesses 6 in the side walls of the movable member 4—see Figure 3.

Accommodated in the lower end of the shank 3 is a lever handle 7, which is pivoted to said shank by means of a removable pin or screw 8 passed through an elongated hole 9 in said lever handle and through one of a series of adjustment holes 10 formed in the arms 5 of the shank.

The lever handle is provided at its upper end with an extension 11 arranged to project into a slot 12 formed in the lower end of the movable jaw member 4. A hole 13 in said handle extension 11 receives a pin or rivet 14, which is passed through the lower end of the movable jaw member 4 to thus pivotally connect the lever handle thereto.

In use, the jaws of the wrench are first adjusted approximately to the size of nut to be turned by inserting the removable pin or screw 8 into a selected one of the adjustment holes 10 in the slotted shank 3. The wrench is then applied to the nut and the lever handle 7 grasped and actuated similarly to the handle of an ordinary wrench. In the initial movement, the lever handle pivotally moves on the pin 8 causing the extension 11 of said handle to slide the movable jaw member 4 upwardly into engagement with the nut. Further operation of the lever handle now tightly closes the jaws upon the flats of the nut and causes the nut to be rotated in the usual manner. Upon relaxing the pressure upon the lever handle 7, the jaws are released from gripping engagement with the nut.

In wrenches, the faces of the jaws 2 and 4 are made straight and are serrated as shown in the drawings to enable a firm grip to be obtained, but in pipe wrenches and like tools the faces of the jaws are preferably curved.

What I do claim is:—

An improved adjustable wrench comprising a fixed L-shaped member having a slot extending longitudinally of the long leg of said member and dividing said long leg into two sections, the said long leg having a series of holes therethrough, a jaw face formed on the short leg of said member, a sliding jaw mounted between the sections of the long leg of the L-shaped member, an L-shaped handle having a slot formed in the corner thereof, the short leg of said handle being pivoted to the said sliding jaw, and a pin removably connecting the handle with the fixed L-shaped member by passing through said corner slot and any one of the holes in the long leg of the L-shaped member.

In testimony whereof I affix my signature.

WILLIAM HENRY GOLDSTRAW.
